UNITED STATES PATENT OFFICE.

JOSEPH L. WELLS, OF PHILADELPHIA, PENNSYLVANIA, ASSIGNOR TO THE WESTON AND WELLS MANUFACTURING COMPANY, OF CAMDEN, N. J.

HAIR-ROLL.

SPECIFICATION forming part of Letters Patent No. 337,642, dated March 9, 1886.

Application filed March 12, 1885. Serial No. 158,525. (No model.)

To all whom it may concern:

Be it known that I, JOSEPH L. WELLS, a citizen of the United States, residing in the city and county of Philadelphia, and State of Pennsylvania, have invented certain new and useful Improvements in Hair-Rolls, of which the following is a full, clear, and exact description, reference being had to the accompanying drawings.

- 10 Figure 1 is a side elevation of a braided steel-wire cylinder from which my improved hair-roll is formed. Fig. 2 is an end elevation of Fig. 1. Fig. 3 is a side view of the finished roll. Fig. 4 illustrates the application thereof.
- 15 The nature of this invention is a braided or woven wire roll for puffing or supporting the hair, and its object is to provide such a toilet article that shall be light, cool, airy, and resiliant.
- 20 The invention also comprises details of construction, as will hereinafter appear.
- Referring to the accompanying drawings, *a*, Fig. 1, represents an open hollow cylinder of light-tempered steel or other wire of any suitable dimensions, Fig. 2 being an end view or transverse section thereof. The wires composing the same are braided into a continuous roll by known machinery. The cylinder is highly elastic in all directions. In order to 30 give the same the usual form of a hair-roll tapering toward each end from about the middle, I draw together the ends of the cylinder—the great flexibility of the fabric readily permitting this to be done—and secure the free extremities of the wire bunch by means of metallic clips or buttons *b*, as shown in Fig. 3. These clips serve also to cover over the end wires which would, if left free, be apt to prick the head of the wearer of the roll.
- 40 In order to present a flat-surface contact to the forehead or other part, I flatten the side of the roll, (either during the process of braiding the wire or subsequently,) as indicated at *c* by the end view, Fig. 2, and also in Fig. 3. The

flattening of the tubular fabric on one side gives 45 a firmer resistance to pressure upon the top or round part of the roll than if the same were made wholly tubular. This construction is applicable in connection with braided-wire cylinders to various purposes other than hair- 50 rolls, and will form the subject-matter of a broad claim in an application for Letters Patent which I propose filing during the pendency of this application.

The roll is secured to the head of the wearer 55 in any suitable manner—for example, by means of an elastic cord, *d*, whose ends are attached to the respective ends or clips *b* of the roll.

The mode of applying and using the device, 6 , as indicated in Fig. 4, being well known requires no special description.

If the hair which is laid over the roll is thin, it is desirable to apply to the latter a covering, temporary or otherwise, of netting 65 or other fabric corresponding in color to that of the hair, so that the sheen of the wire will not be visible through the hair.

It is obvious that by this construction I fully attain the object of the invention, as hereinbefore stated. I do not wish, however, to be understood as confining myself to the precise form or construction described, nor to the use of a braided wire-fabric; but

What I claim as new, and desire to secure 75 by Letters Patent, is—

A hair-roll composed of a tube of braided elastic wire having its ends drawn together and fastened by means of buttons, one side of the tube being flattened to set comfortably and 80 securely upon the head of the wearer, substantially as specified.

In testimony whereof I have hereunto affixed my signature.

JOSEPH L. WELLS.
